UNITED STATES PATENT OFFICE.

WILLIAM J. HAUSSLER, OF BROOKLYN, NEW YORK, ASSIGNOR TO THE FIRM OF
M. HOHNER, OF NEW YORK, N. Y.

DISPLAY-STAND.

1,093,327.

Specification of Letters Patent. Patented Apr. 14, 1914.

Application filed November 5, 1913. Serial No. 799,260.

To all whom it may concern:

Be it known that I, WILLIAM J. HAUSSLER, a citizen of the United States, residing at Brooklyn, county of Kings, and State of New York, have invented a new and Improved Display-Stand, of which the following is a specification.

This invention relates to a display stand for harmonicas and similar articles of merchandise, which effectively shows off the goods, is of compact form, and may be readily set up or folded.

In the accompanying drawing: Figure 1 is a front view of a display stand embodying my invention; Fig. 2 a rear view thereof; Fig. 3 a rear view showing the parts in a different position; Fig. 4 an edge view on a reduced scale showing the device folded, and Fig. 5 a longitudinal section of Fig. 3.

The device comprises essentially a face plate 10 of suitable ornamental configuration, and adapted to be folded along a transverse scored line 11, which is reinforced by a strip of webbing 12. To the rear side of face plate 10, there is pasted or otherwise secured a smaller back plate 13 which is adapted to constitute a prop, and which is provided for that purpose on each side with an integral foldable wing 14, said wing being disconnected from the face plate and adapted to stand off the same at an angle. From each edge of the back plate proper there extends a hook 15 made integral therewith, and adapted to be turned into a horizontal position on a lower scored line 16. Hook 15 is accommodated by a corresponding aperture 17 of wing 14 (Fig. 2) and when the device is to be set up, each wing is turned backward, and then hook 15 is turned down, so as to pass through the aperture and engage the outer face of the wing (Fig. 3) thus locking the wing at an angle to the face plate 10. In this way the wings will fur-

nish a base or prop for the device, by means of which it will be sustained in an upright position on a counter or similar support.

Above the scored line 11, the back plate 13, together with its wings 14 is entirely detached from the face plate, to form a horizontal flap 18 which is foldable along a transverse scored line 19, that registers with line 11. Flap 18 is provided with an eye 20, through which extends a turn button 21 pivoted to the upper foldable section 10^a of face plate 10, as at 22, and slightly set off from the same by a block 23.

When the device is to be folded, the turn button is caused to release flap 18 so that the back plate can be doubled conjointly with the face plate, while when the device is unfolded the turn button is caused to engage the flap and lock the back plate to the face plate, so that in this way the upper foldable section 10^a of the face plate, will be likewise sustained in an upright position upon the spreading of the wings 14 into the position shown in Figs. 3 and 5.

Means are provided on the face plate for securing suitable articles of merchandise thereto, the drawing showing it to carry U shaped clasps 24, which are more particularly adapted for the reception of harmonicas, though other suspending or sustaining devices may obviously be employed.

I claim:

A display stand comprising a face plate, having an upper foldable section, a back plate having an upper apertured flap, a turn button on the foldable section of the face plate adapted to be projected through the flap-aperture, and means on the back plate for sustaining it in an upright position.

WILLIAM J. HAUSSLER.
